ELECTRICAL RELAY HOUSING

Hermon L. Van Valkenburg, Wauwatosa, Wis., assignor to Square D Company, Detroit, Mich., a corporation of Michigan

Application February 19, 1936, Serial No. 64,628

5 Claims. (Cl. 200—168)

This invention relates generally to a device for making and breaking electrical circuits and more particularly to an electromagnetically operated relay.

5 One object of the invention is to provide a sturdy but very compact electromagnetically operated relay.

Another object of the invention is to provide an improved mounting means for an electrical relay within a closing box providing simplicity, 10 economy and compactness.

Another object of the invention is to provide an improved form of contact finger assembly for double throw relays in which a resilient contact 15 pressure is exerted in both positions of the finger.

Another object of the invention is to provide an improved form of mounting for a contact finger in which the finger moves relative to its 20 operating member in opposite directions against a spring, whereby a resilient contact pressure is maintained in both directions by a very simple mechanism, while the extreme positions of the operating member are positively limited.

25 Other objects and features of the invention will be readily apparent to those skilled in the art from the following specification and appended drawing illustrating certain preferred embodiments of the invention in which:

30 Figure 1 is a front elevational view of the electrical relay according to the present invention with a portion of the cover cut away showing the internal mechanism.

Figure 2 is a vertical sectional view taken on 35 the line II—II of Figure 1.

Figure 3 is a horizontal sectional view on the line III—III of Figure 1.

Figure 4 is a view similar to Figure 2 showing the parts in the energized position.

40 Figure 5 is a horizontal sectional view on the line V—V of Figure 1.

The relay according to the present invention comprises a metallic enclosing box 1 having a removable cover 2 attached by studs 3 to lugs 4 secured to the box walls. The end walls of the box may be provided with knockout openings for the reception of conduit attachment fittings as at 5. The back wall of the box, adjacent the top and bottom, is provided with openings 6 for the reception of attaching screws. A sheet of fibre or other insulation 7 is provided immediately adjacent to the back wall of the box. In order to provide very small size, the relay mechanism is supported within this box 55 by means of a generally U-shaped insulating

sheet 8 of fibre or other material. The mechanism is mounted generally centrally of this sheet and the edges thereof are then bent upwardly into the U-form with the base having a width equal to the interior width of the box. 5 Due to the flexible nature of the sheet, the legs thereof will closely and resiliently engage the side walls of the box. These legs terminate closely adjacent to the top of the box and when the cover is in place it will engage the outward 10 edges of the insulating sheet and maintain the relay mechanism in position in the box. In order to keep the attachment opening 6 uncovered, the sheet 8 terminates short of the end walls of the box and guide pins 9, rigidly secured to the 15 box, are provided to maintain the sheet in a central position within the box with the openings uncovered.

The relay mechanism includes a rigid insulating base 11 having mounted thereon adjacent its upper end a pair of opposed stationary contacts 12 and 13 and terminal connectors 14 and 15 electrically and mechanically attached thereto. These are mounted on the base by studs 16 and 17 which extend through the insulating sheet 25 8 and also serve to rigidly secure the base 11 to this supporting sheet. An L-shaped supporting member 18 may be riveted or otherwise secured to the base 11 and is preferably formed of 30 conducting and magnetic material and is provided with a pair of terminal connectors 19 and 21. The supporting angle 18 is provided adjacent its front corners with a pair of projecting tongues 22 received in corresponding slots in an angle armature member 23. One side of this 35 armature member is notched as is shown in Figure 5, providing clearance for a biasing spring 24 connected between the base 11 and the armature member 23 and biasing the latter to its unenergized position more particularly shown in 40 Figure 2. The support 18 is provided with a pair of stops 25 for positively limiting the de-energized position of the armature 23. A magnetic core 26 having an operating coil 27 therearound is mounted against the rear leg of the supporting 45 member 18 and is secured in position by a stud 28 which passes through the supporting sheet 8, the base 11 and the rear leg of member 18 and is threaded into the core 26, holding the parts securely together. A shading coil 29 may be 50 provided embedded in the front face of the core 26. The magnetic path is through the core 26, supporting member 18 and the armature 23, all of which are formed of magnetic material. It will be readily seen that if the coil 27 is ener- 55

gized the armature 23 will be moved in the position shown in Figure 4.

A contact finger 31 is mounted on the armature 23 and has opposite contact faces thereon disposed between the stationary contacts 12 and 13. The armature member 23 is provided at its front face with a pin 32 which loosely projects through the contact finger 31. A spring 33 is disposed around the pin 32 in front of the contact finger and is secured in position by a washer and cotter pin as shown. The contact finger 31 is provided with tongues 34 received in corresponding slots in the armature 23 to prevent rotative movement therebetween. The contact finger is provided with what may be termed a flat depressed surface 35 through which the pin 32 projects, which surface extends for some distance above and below the pin. The edges of the surface 35 constitutes axes about which the contact finger 31 rotates relative to the armature 23. As can readily be seen, this rotation is off-center with relation to the pin 32 and results in a compression of the spring 33 which serves to exert a resilient contact pressure. The extreme positions of the armature 23 are positively limited by the front face of the magnetic core 26 and by the stops 25, and the stationary contacts 12 and 13 are so located as to be engageable with the contact faces on the finger 31 before the armature member reaches its extreme positions. This results in a turning movement of the finger 31 in opposite directions about the axes formed by the edges of the surface 35 and hence results in a resilient contact pressure being maintained by the spring 33 between the contact faces on the finger 31 and both of the contacts 12 and 13. This results in a desirable and extremely simple construction for securing a resilient contact pressure in both directions by a single spring mounting for the contact finger.

A flexible lead 38 extends from the terminal connector 19 to the bottom of the contact finger where it is securely attached as by means of a rivet 39. The terminal 21 is adapted for connection to an exterior circuit wire by which an electrical connection to the contact finger 31 is made through supporting member 18, connector 19 and flexible lead 38 to the contact finger. Connections to the stationary contacts 12 and 13 may be made at the terminal connectors 14 and 15, respectively. Terminals 41 and 42 are provided for the operating coil 27.

The operation of the relay described should be readily apparent. The parts as shown in Figures 1 to 3, inclusive, and 5 are in the de-energized position where the armature member 23 is held by the spring 24 against the stops 25. In this position the contact finger is rotated about the upper edge of the surface 31 with respect to the armature 23 and the contact finger is resiliently pressed against the stationary contact 12 by the spring 33. When the relay is energized by the closing of the circuit through the operating coil 27, the armature member 23 will be attracted into engagement with the front face of the core 26. The parts will assume the position shown in Figure 4 with the armature member engaged with the magnet core and the contact finger 31 rotated about the lower edge of the surface 35 with the contact finger resiliently pressed against the stationary contact 13 by means of the spring 33. When the operating coil 27 is again de-energized, the parts will again assume the position as shown

in Figures 1 to 3, inclusive, and 5 with the contact finger engaged with the stationary contact 12.

While certain preferred embodiments of the invention have been specifically disclosed, it is understood that the invention is not limited thereto as many variations will be readily apparent to those skilled in the art and the invention is to be given its broadest possible interpretation within the terms of the following claims: 10

What is claimed is:

1. Housing and mounting means for an electromagnetically operated electric relay comprising an outer metallic box of a size to relatively closely receive said relay and its associated elements, a generally U-shaped piece of relatively flexible insulating material, the base of the U being of a width substantially conforming to the interior box width and having said relay mounted thereon, said U-shaped piece being disposed in the box with its side walls in engagement with the side walls of the box and forming substantially the entire structural support for said relay within the box, the front edges of the side walls of the insulating material terminating in substantially the same plane as the side walls of the box, and a cover for said box rigidly mountable thereon and, when in closed position, preventing forward movement of said insulating material within the box. 20

2. Housing and mounting means for an electric relay as defined in claim 1 in which the box is provided with interior guide means engageable with the edges of the insulating material to maintain the edges spaced from the ends of the box. 30

3. Housing and mounting means for an electric relay as defined in claim 1 in which the back of the box is provided with openings for supporting screws adjacent the top and bottom thereof, and with a separate insulating sheet serving to insulate the back of the box from elements on the back face of the base of the U-shaped piece, and guide pins on the back wall of the box adjacent the top and bottom thereof and engageable with the edges of the U-shaped piece to maintain the attachment openings uncovered. 40

4. Housing and mounting means for an electromagnetically operated electrical relay comprising a rigid insulating base having said relay mounted thereon, an elongated, flexible, fibre sheet, said base being supported on said sheet substantially centrally thereof, an outer enclosing box having an openable cover, the ends of the sheet being bent outwardly to form a U-shaped structure received within said box with the legs of the U engaging the side walls of the box and with their outer edges engageable by the cover in its closed position to maintain the base and its supported mechanism in position within the box. 50

5. Housing and mounting means for an electric circuit controlling device comprising an outer metallic box, an insulating sheet bent into a substantially U shape, with the base of the U of a width conforming to the interior box width so that the legs of the U, when disposed within the box, are in engagement with the side walls of the box, the circuit controlling device being mountable upon the base of said U-shaped insulating sheet, and means for maintaining said U-shaped insulating sheet in its interior position within the box and supporting the circuit controlling device in operating position therein. 60
